POLE

Maurice J. Rhude, Marinette, Wis., assignor to Koppers
Company, Inc., a corporation of Delaware

Filed Aug. 1, 1967, Ser. No. 8,084

Term of patent 14 years

(Cl. D26—12)

The figure is a perspective view of a pole showing my new design as seen from the front and side. The rear of the article is identical in appearance to the front, and the side away from the side shown in the drawing is identical in appearance to the side shown in the drawing.

The broken line showing of insulators and power lines is for illustrative purposes only.

I claim:

The ornamental design for a pole, as shown and described.
